UNITED STATES PATENT OFFICE.

SIMON B. MINNICH, OF LANDISVILLE, PENNSYLVANIA.

LIFTING AND COMPRESSING DEVICE.

SPECIFICATION forming part of Letters Patent No. 416,733, dated December 10, 1889.

Application filed August 1, 1888. Serial No. 281,642. (Model.)

To all whom it may concern:

Be it known that I, SIMON B. MINNICH, a citizen of the United States, residing in Landisville, in the county of Lancaster and State 5 of Pennsylvania, have invented certain Improvements in Lifting and Compressing Devices, of which the following is a specification.

My invention relates to that class of devices used for extracting stumps, raising heavy bodies, and compressing the platens of tobacco, hay, and other similar presses; and my object is to use eccentrics with grips attached to the eyes thereof for that purpose, 15 preferably employing two, moving about the same center of motion, those adjacent to each other having their greatest eccentricity on opposite sides of that center.

My invention consists in the combination 20 of a hanger having a drop connected therewith supporting an eccentric-shaft, eyes fitting over the eccentrics and pivotally connected with grips which engage tension rods or racks.

My invention consists, also, in the peculiar 25 construction of the drop attached to the hanger, as will be hereinafter fully described and claimed.

In the accompanying drawings I show a 30 portion of an end and side of a press for which Letters Patent No. 366,339 were granted me July 12, 1887, to illustrate the application of my invention to a press.

Figure 1 is a side view of my device, the 35 drop being taken up and the upper grip biting on the tension-rod. Fig. 2 is a front view of the same, the tension-rod being partially cut away. Fig. 3 represents a front view of the eccentric-shaft detached and in the position occupied by it in the two previous figures, the eyes being in section. Fig. 4 is a side view of the drop extended, and Fig. 5 a top view of the same when taken up. Fig. 6 shows the pawl-and-ratchet attachment; Fig. 45 7, a side view of the rack-bar, and Fig. 8 a top view of the grips used therewith. Fig. 9 represents the device supported by a tripod.

In the drawings, C represents the press, and S the press-beam.

50 a a are jaws rigidly secured to the lower portion of the sectional hanger A A'.

B is a shaft journaled in those jaws.

J represents an eccentric formed upon the center of the shaft B, and D D are smaller eccentrics on each side of it, having their 55 greatest eccentricity on the side of the shaft opposite to that of the center eccentric.

There is a slot L cut through the upper end of the section A of the hanger, by means of which it is connected with the press-beam 60 when the device is used with a press, or by which it is engaged by a hook when supported by a tripod.

E is the eye fitting over the eccentric J, and has the arm e rigidly attached thereto. 65 To this arm, jaws f f, formed integral with the annular grip F, are pivotally connected. Eyes G G fit over the eccentrics D D in a similar manner, each one being provided with an arm g, rigidly secured thereto. Each arm 70 has an aperture through the outer end, through which a pin H passes, the annular grip K being loosely connected with the pin between those arms by the arm k, formed integral with the grip. 75

A tension-rod I is secured to the bottom of the press or any body to be raised, and this rod is engaged by the annular grips F and K. At each revolution of the shaft B the 80 grips are alternately raised and lowered by the action of the eccentrics with which they are connected.

By the arrangement of the eccentrics herein described the turning of the shaft B alternately raises and lowers the grips F and K. 85 As the grips are supported on one side only, they set diagonally about the tension-rod I when engaged therewith, as shown in Figs. 1 and 9. This position causes the lower front edge of the openings through the grips and 90 the upper rear edge of the same to bear against the rod I, so that when the movement of the eccentric with which either grip is connected tends to raise it those edges bite into the tension-rod and grip it firmly. So, too, the 95 lowering of the grips as the eccentrics descend with the revolution of the shaft causes them to slide down the tension-rod preparatory to again taking hold of it as the eccentrics rise. The instant the eccentric to which 100 one of the grips is attached begins to rise that grip takes hold of the tension-rod and maintains its grasp until the eccentric again begins to descend, when it immediately

loosens its grasp; and as the eccentrics supporting the two grips are opposite each other as soon as one eccentric begins to rise the other begins to descend, so that the moment 5 one grip takes hold of the tension-rod the other loosens on it and slides down to again grasp it. In this description of the action of the grips the two eccentrics D D, to which the grip K is attached, are regarded as one, 10 they being arranged in the manner described to keep the centers of the grips in the same vertical plane. In the application of my device to a press, as illustrated in the accompanying drawings, each grip alternately draws 15 upon the press-beam S as the eccentric to which it is attached rises with the revolution of the shaft B.

When the bite of the grip on a smooth rod is not sufficient to prevent them from slipping, 20 a rack-bar T (shown in Fig. 7) may be used. This bar I make flat and the ends of the openings through the grips that engage the rack rectangular.

The shaft may be rotated by means of a 25 crank M or by a lever N, loosely connected with the shaft, held in place by a nut m, and carrying a pawl n, which engages a ratchet p, rigidly secured to the shaft.

The result of the action attained by the 30 use of double eccentrics and grips herein described could be accomplished by the use of one, although it would require double the number of revolutions of the shaft to perform the same amount of work. In this 35 case but one of the grips is connected with an eccentric, while the end of the arm to which the other is pivoted is secured to the press-beam. As the grip connected with the eccentric draws upon the tension-rod and 40 pulls the press-beam downward the other or second grip slips down the tension-rod, and when the first grip loses its hold as the eccentric passes beneath the shaft the upward pull of the press-beam engages the 45 second grip with the tension-rod, and the beam is thereby held down until the tension-rod is again grasped by the grip connected with the eccentric.

When used to extract stumps or raise 50 bodies from the ground, the device is upheld by a tripod, the slot L of the hanger being engaged over a hook 9 dependent from the apex thereof, as shown in Fig. 9, or is supported in any other convenient manner.

55 A A' represent the two sections of the hanger. These are connected by a link Q, pivoted to their inner ends. Recesses R are formed in the adjacent faces of those ends of the hanger-sections, as shown in Figs. 1 60 and 4, to throw the link as nearly in the direct line of strain as possible when the drop is doubled up. When so doubled up, the

inner ends of the sections A and A' lap each other, throwing the point of connection of the link with the upper section below and in 65 a vertical line with that of the lower. In this position the upper end of the link, which projects beyond the end of the section A', is engaged on both edges by a stop V on a hand-lever W, pivoted at y to the section 70 A. These stops prevent any accidental opening of the drop. I prefer these drops, as when opened they hold the parts together, and when used on a press prevent the press-beam from being thrown out of the slots in 75 which it works by the reaction caused by loosening the grip of the device upon the tension-rod. In lifting a weight this is not so important, and any kind of a drop may be used. 80

Having thus described my invention, what I claim as new, and desire to secure by Letters Patent, is—

1. The combination, with the eccentric-shaft, of eyes fitted over the eccentrics of the 85 shaft, grips pivotally connected with the eyes, and the tension-rod, substantially as and for the purpose specified.

2. The combination, with the shaft having a centrally-located eccentric and an eccentric formed on each side thereof, the center eccentric having its greatest eccentricity on the side of the shaft opposite to that on which the greatest eccentricity of the others is placed, of an eye E, fitting over the center 95 eccentric, having an arm rigidly attached thereto, and a grip having jaws f f formed integral therewith, between which the arm of said eye is pivoted, eyes G G, fitted over the side eccentrics, each provided with a 100 rigid arm g and a grip K, having an arm formed integral therewith, and pivoted between the arms g, and a tension-rod, substantially as specified.

3. The combination, with a hanger divided into two sections, of a link pivotally connected with said sections, and a hand-lever pivoted to one of the sections and provided with stops for engaging the end of the link when the ends of the sections lap each 110 other, substantially as and for the purpose specified.

4. The combination, with the sectional hanger, of a link pivotally connecting the sections, and a stop adapted to bind the link 115 and sections together when the ends of the sections lap each other and prevent the extension of the sections and the link, substantially as specified.

SIMON B. MINNICH.
